Charles D. Lyon
INVENTOR
BY Victor J. Evans

ATTORNEY

UNITED STATES PATENT OFFICE.

CHARLES DOWNEY LYON, OF CHICAGO, ILLINOIS.

HAT RETAINER.

Application filed August 30, 1924. Serial No. 735,189.

To all whom it may concern:

Be it known that I, CHARLES D. LYON, a citizen of the United States, residing at 1104 N. Dearborn St., Chicago, in the county of Cook and State of Illinois, have invented new and useful Improvements in Hat Retainers, of which the following is a specification.

This invention relates to a hat retainer and 10 has for its primary object the construction of a simple device that may be readily inserted in a hat and when in place will effectively grip the head of the wearer. An object of the invention is the use of a suction 15 device that may be readily arranged in place to properly engage the head.

With these and other objects in view the invention will be better understood from the following description taken in connection 20 with the accompanying drawing, wherein:

Fig. 1 is a sectional view illustrating the application of my invention,

Fig. 2 is a similar view showing the device in operation,

25 Fig. 3 is a front elevation and

Fig. 4 is a detail view of portion of the hat band.

Again referring to the drawing illustrating one of the many constructions of my invention, the numeral 1 designates an ordinary hat band in which is formed a button-hole 2. My improved hat retainer comprises

a cup-shaped body 3 which may be formed from rubber or other yieldable material so as to have a suction action with the head of the wearer. This body is provided with a neck 4 to which is attached a button 5 for passage thru the hole 2 for holding the retainer in place.

From the foregoing description taken in 40 connection with the accompanying drawing, it will be apparent that I provide a simple device that may be readily arranged in place and which will have an effective gripping action with the head of the wearer for holding the hat in place.

It is, of course, to be understood that the invention may be constructed in various other manners and the parts associated in different relations, therefore, I do not desire 50 to be limited in any manner except as set forth in the claims hereunto appended.

Having thus described my invention what I claim is:

1. In combination with a hat band having 55 a button hole, a cup shaped resilient holder having a button for passage through said hole.

2. In combination with a hat band a cup-shaped suction holder having a connection 60 with the hat band.

In testimony whereof I affix my signature.

CHARLES DOWNEY LYON.
